US0D1096683S

(12) **United States Design Patent** (10) Patent No.: **US D1,096,683 S**
(45) Date of Patent: ** Oct. 7, 2025

(54) **DISPLAY FOR AN ELECTRONIC GAMING MACHINE**

(71) Applicant: **Aristocrat Technologies Australia Pty Limited**, North Ryde (AU)

(72) Inventor: **Rajendrasinh B. Jadeja**, Las Vegas, NV (US)

(73) Assignee: **Aristocrat Technologies Australia Pty Limited**, North Ryde (AU)

(**) Term: **15 Years**

(21) Appl. No.: **29/979,620**

(22) Filed: **Dec. 19, 2024**

Related U.S. Application Data

(63) Continuation of application No. 29/792,423, filed on Mar. 28, 2022, now Pat. No. Des. 1,061,466, which is a continuation of application No. 29/788,408, filed on May 18, 2021, now Pat. No. Des. 948,621, which is a continuation of application No. 29/673,951, filed on Dec. 18, 2018, now Pat. No. Des. 923,592.
